(57) **CLAIM**

The ornamental design for a computer screen with graphical user interface, as shown and described.

DESCRIPTION

The patent or application file contains at least one drawing executed in color. Copies of this patent or patent application publication with color drawing(s) will be provided by the Office upon request and payment of the necessary fee.

2.1 is a front view of a first image of a computer screen with graphical user interface;

2.2 is an enlarged view of the first image shown in **2.1**, the graphical user interface is shown separately for clarity of illustration;

2.3 is an enlarged view of the second image, the graphical user interface is shown separately for clarity of illustration;

2.4 is a back view of the computer screen with graphical user interface;

2.5 is a left view of the computer screen with graphical user interface;

2.6 is a right view of the computer screen with graphical user interface;

2.7 is a top view of the computer screen with graphical user interface; and

2.8 is a bottom view of the computer screen with graphical user interface.

The broken lines showing the computer screen in FIGS. **2.1** and **2.4-2.8** form no part of the claimed design. The broken

(Continued)

line showing of portions of the graphical user interface in FIGS. 2.1, 2.2 and 2.3 form no part of the claimed design. The appearance of the image transitions sequentially between the images shown in reproductions 2.2-2.3. The process or period in which an image transitions to another forms no part of the claimed design.
